UNITED STATES PATENT OFFICE.

HERCULES PERVELIS, OF NEW YORK, N. Y.

SECTIONAL GUN.

1,163,450.

Specification of Letters Patent.

Patented Dec. 7, 1915.

Application filed February 27, 1915. Serial No. 10,985.

To all whom it may concern:

Be it known that I, HERCULES PERVELIS, a subject of the King of Greece, residing at New York, in the county of New York and 5 State of New York, have invented new and useful Improvements in Sectional Guns, of which the following is a specification.

This invention relates to a gun composed of a series of sections with means for 10 detachably connecting the sections together and it consists in the novel features herein-after described and claimed.

An object of the invention is to provide a structure especially adapted to be used in 15 connection with guns of large caliber whereby a gun composed of sections is provided, the said sections being adapted to interfit with each other at their ends and means being provided for securely holding the sections in place with relation to each other 20 when the gun is in use. The said sections are also detachable from each other and may be packed in compact space for transportation or other purposes.

25 A prime object of the invention is to provide a gun which may be easily and quickly transported from point to point over rough country due to the fact that the sections may be detached from each other and readily carried upon pack animals or other transporting means. When the component parts have been assembled at a desired point and connected together a gun of comparatively large 30 caliber is had in a position which by reason of lack of usual approaches could not be used in military operations by reason of the impossibility to set up the usual artillery pieces and the impossibility of transporting the said pieces to the said locality.

40 With these objects in view the gun comprises a series of sections which interfit at their ends one with the other and which are bored at a uniform diameter. These bores register with each other when the sections 45 are connected and constitute a complete bore for the gun. The said sections are provided at their adjacent ends with right and left screw threads and nuts of peculiar design and pattern are arranged to engage the said 50 threads and draw the ends of the sections in close contact with each other thereby preventing the escape of gases between the

ends of the sections when the gun is fired. Locking means are provided for holding the said nuts against turning movement when in 55 position upon the gun sections but the said locking means are of such structure as to be readily manipulated for the purpose of releasing the nut when it is desired to disconnect the sections of the gun one from the 60 other.

In the accompanying drawing:—Figure 1 is a side elevation of the gun with parts in section. Fig. 2 is a side elevation of parts of the gun separated and showing portions in 65 sections. Fig. 3 is an end view of one of the nuts with part in section. Fig. 4 is a transverse sectional view of a portion of one of the sections of the gun cut on the line 4—4 of Fig. 2. Fig. 5 is a perspective view of 70 parts of the nut locking means provided upon the gun section.

The gun may be composed of any desired number of sections but for the purpose of illustration a gun of three sections is shown 75 and described. Sections of the gun are indicated at 1, 2 and 3. The section 1 is the breech section, the section 2 is an intermediate section and the section 3 is the muzzle section. All of these sections are provided 80 with a bore 4 and when the sections are connected with each other the said bores are in longitudinal alinement with each other and constitute the bore for the assembled gun structure. All of the gun sections except 85 the muzzle section 3 are provided at their forward ends with counter bores 5 of greater diameter than the bores 4. The intermediate and muzzle sections are provided at their rear ends with bosses 6 adapted to fit 90 snugly in the counter bores 5 as best shown in Fig. 1 of the drawing. The intermediate and muzzle gun sections 2 and 3 are provided at their rear ends with pins 7 which fit snugly in sockets 8 provided at the forward ends of the breech and intermediate sections respectively. The breech and intermediate sections 1 and 2 are provided at 95 their forward ends and upon their peripheries with longitudinally disposed recesses 9 and threads 10 are provided upon the peripheries of the said sections at the portions thereof which lie between the recesses 9. The threads 10 at the opposite sides of the

recesses 9 are in spiral alinement with each other but the presence of the recesses 9 in the said threads interrupts the continuity of the same. As shown the threads 10 are right hand threads.

The intermediate and muzzle gun sections 2 and 3 are provided at their rear ends with recesses 11 similar to the recesses 9. The sections 2 and 3 are provided upon those 10 portions which lie between the recesses 11 with threads 12 and the portions having the threads 12 are adapted to be brought against the ends of the portions having the threads 10 when the sections are assembled. The 15 threads 12 are disposed opposite to the threads 10 and inasmuch as the threads 10 are right hand threads the threads 12 are left hand threads. When the sections are assembled the recesses 11 are in longitudinal 20 alinement with the recesses 9 and the pins 7 are received in the sockets 8.

Nuts 13 are provided for connecting the section 2 with the section 1 and the section 3 with the section 2 and as these nuts are of 25 the same design and configuration a description of one will answer for both. Each nut 13 is provided at its inner side with threaded spurs 14 the threads upon the spurs at the opposite ends of the nuts being 30 disposed in opposite directions and adapted to engage the threads 10 and 12 respectively. Prior to engaging the threads 10 and 12 the spurs 14 are received in the recesses 9 and 11 consequently when the nuts 13 are 35 turned upon the sections the adjacent sections are drawn at their ends into close contact with each other. Each nut 13 is provided in its interior and between its ends with an annular cavity 15 and the said 40 cavity fits over the adjacent ends of the abutting sections when the parts are assembled and serves as a trap for receiving any gas that may escape between the adjacent ends of the sections when the gun is fired. 45 This prevents the gas from entering between threads 14, 10 and 12 and corroding or damaging the same. Each nut 13 is provided at its rear face with a series of recesses 16 spaced at regular intervals apart. Each nut 50 13 is provided upon its periphery with a series of teeth 17 with which a wrench (not shown) may be connected for the purpose of turning the nut. A locking device is provided upon each of the sections 1 and 2 for 55 locking the nuts 13 in position when applied and each of said locking devices comprises a plate 18 secured to the section and having stops 19 mounted thereon. Bolts 20 are also mounted upon the plate 18 and 60 pass through the stops 19 and a plate 21 is loosely mounted upon the bolts 20. Nuts 22 are screw threaded upon the bolts 20 and are adapted to engage at their under faces the plate 21 and hold the same in a fixed 65 position with relation to the stops 19. Lugs

23 are mounted upon the plate 21 and a traction bolt 24 passes through the lugs 23 and is provided with a nut 25 which when tightened is adapted to draw the lugs 23 toward each other. A pin 26 lies between the 70 lugs 23 and when the bolt 24 is tightened the said pin 26 is grasped and held against movement with relation to the said lugs. A lever 27 is fulcrumed upon the pin 26 and is provided with a forked end 28 which engages behind a head 29 of a stud 30 carried by a block 31. The block 31 lies between the plates 21 and 18 and when the nuts 22 are tightened upon the bolts 20 the intermediate portion of the plate 21 clamps the 80 block 31 upon the plate 18 whereby the said block is held in a stationary position with relation to the said plate. The block 31 is provided with pins 32 which are adapted to enter the recesses 16 and thus the nuts 13 85 are held against turning movement.

When it is desired to disconnect the sections 1, 2 and 3 from each other the nuts 22 are loosened whereby the blocks 31 are released then the levers 27 are swung so that the blocks 31 are moved longitudinally and the pins 32 are withdrawn from the recesses 16. Thus the nuts 13 are released and they may be turned to cause their threads 14 to disengage from the threads 10 and 12 95 and enter the recesses 9 and 11. When this has been done the sections may be moved longitudinally with relation to each other and disconnected from one another.

When the parts are assembled the operations above described are reversed and prior to tightening the nuts 22 the blocks 31 may be moved between the plates 21 and 18 to bring the pins 32 into desired recesses 16 and after the said pins enter the recesses the 100 nuts 22 are tightened whereby the nuts 13 are held against turning movement upon the sections and then the nut 25 upon the bolt 24 is tightened so that the pin 26 is held against turning movement between the 110 lugs 23.

From the above description taken in conjunction with the accompanying drawing it will be seen that a gun of simple and durable structure is provided and the sections which composed the gun may be easily and readily detached from each other for transportation and when the said sections are brought together they may be quickly and effectually secured in position with relation to each other to permit of the use of the gun for firing projectiles in the usual manner.

Having described the invention what is claimed is:—

A gun comprising sections adapted to 125 abut one against the other at their ends, nuts having screw thread engagement with the sections and adapted to draw them in close contact with one another, a plate mounted upon one section and having stops, 130

a second plate mounted upon the first mentioned plate and adapted to engage the stops, means for securing the second mentioned plate in position with relation to the 5 stops, a block movably mounted between the plates and adapted to be passed between them, pins carried by the block and adapted to enter the nut to hold the same against turning movement and a lever mechanism adapted to move the block. 10
In testimony whereof I affix my signature in presence of two witnesses.

HERCULES PERVELIS.
